ALBERT A. WELLS, OF DETROIT, MICHIGAN.

SPARK-PLUG.

1,354,361.

Specification of Letters Patent. Patented Sept. 28, 1920.

Application filed September 26, 1919. Serial No. 326,435.

To all whom it may concern:

Be it known that I, ALBERT A. WELLS, a citizen of the United States, and a resident of Detroit, in the county of Wayne and State of Michigan, have invented new and useful Improvements in Spark-Plugs, of which the following is a full, clear, and exact description.

The present invention relates to an improvement in sparking devices which are used for igniting the explosive charge in the working cylinders of internal combustion engines. It has reference more particularly to what are commonly termed spark plugs which are used in connection with the jump spark ignition systems.

Primarily the object of the invention is to provide a spark plug of the type specified in which the working parts may be removed from the engine cylinder independent of the outer shell for the purpose of cleaning the same as well as to enable new parts to be inserted in lieu of the removed parts should it be necessary to replace the parts.

A further object is to provide means for accomplishing the first named object in a simple and convenient manner, preferably, to enable the parts to be removed without the use of tools.

Further objects and advantages will appear upon reference to the accompanying drawing wherein is illustrated the preferred embodiment of the invention.

In said drawing—

Figure 1 is a top plan view of a spark plug embodying the fundamental principles of the invention;

Fig. 2 is a view in elevation;

Fig. 3 is a sectional view on the line 3—3, Fig. 1;

Fig. 4 is a cross section on the line 4—4, Fig. 2;

Fig. 5 is a view in elevation taken at right angles to Fig. 2.

Fig. 6 is a sectional view on the line 6—6, Fig. 1.

Referring to the drawing in detail and according to the preferred embodiment of the invention, the plug consists primarily of two parts, comprising the outer metallic shell 1 having a reduced threaded end 2 to be received within the usual spark plug opening in the engine cylinder. The other part consists primarily of a porcelain or other non-conducting block 3, such, for in-

stance, as a fibrous block, having an elongated extension 4 adapted to be received within a central opening in the shell 1. The part 3 consists of an insulating covering for the central electrode 5 whereby the same may be insulated from the shell 1 but suspended in sparking relation with the grounded electrode 6 and providing a spark gap therebetween. The grounded electrode 6 preferably consists of a metallic cylinder confined between the shell 1 and the covering for the central electrode 5 and with an annular flange 7 adapted to be confined between the upper end of the shell 1 and the shoulder on the block 3 which is provided in producing the elongated end 4. Suitable gaskets or washers 8 and 9 are used on the top and bottom, respectively, of the annular flange 7 to make a tight joint. The top part 75 of the block 3 is recessed as at 10, into which protrudes the end of the central electrode 5, a suitable gasket 11 being employed to insure a tight joint. Overlying the gasket 11 is a disk-shaped metallic contact plate 80 12 which is adapted to underlie and complete a circuit between the central electrode 5 and the contact plate 13, to which is attached the lead wire 14. The connection between the lead wire 14 and the plate 13 may be conveniently made by solder.

Attention is called to the fact that the covering for the central electrode 5 is merely inserted together with the grounded electrode 6 within the central opening of the shell 1. There is no threaded or other permanent connection between these parts. Now, in order that the parts may be securely maintained in position without loss of compression from the cylinder as well as a short circuit, a clamping device is provided consisting of vertical straps 15 disposed on opposite sides of the plug, with their lower ends terminating in an annular ring 16 adapted to surround the reduced end 2 of the shell 1 and bear against the shoulder provided by the reduction in diameter of the end of the shell. Suitable gaskets or washers 17 and 18 are employed to overlie and underlie the annular ring 16. The opposite ends of the straps 15 terminate above the top of the plug and are provided with diametrically opposed openings 19 providing a trunnion bearing for the cam lever 20.

From the above description it will be readily appreciated that when the lever

20 is disposed in locking engagement, pressure will be brought to bear on the pressure block 21 disposed within the recess 10, whereupon the covering for the central electrode 5 together with the electrode 6 will be tightly confined within the central opening in the shell 1. The action of the cam lever 20 on the straps 15 will also exert a pull on the shell 1 which will securely clamp 10 the parts together. Attention is called to the fact that the clamping action, aside from holding the parts together, will also maintain the contact plate 13 tightly against the annular contact plate 12 and insure a proper 15 completion of the circuit between the lead wire 14 and the central electrode.

In removing the parts, the cam lever 20 is manipulated to relieve the pressure on the block 21 whereupon the covering for 20 the central electrode may be removed. The grounded electrode may then be removed next, and any of the parts thus removed may be readily replaced by new parts, should the occasion require it. Of course, the contact plate 13 may be withdrawn through 25 the radial slot in the side of the block 3. This should be disconnected before an attempt is made to remove the other parts. The straps 15 are preferably made of some 30 flexible metal in order that they may be sprung apart to remove the cam lever, as otherwise the cam lever would interfere with the removal of the covering for the central electrode.

35 While I realize attempts have been made to accomplish substantially the same result as proposed by my invention, these previous examples are open to many objections in that they fail to appreciate the advantage 40 of utilizing the clamping means as a medium for maintaining the contact between the central electrode and the lead wire closed under tension. Then again the previously known constructions are prohibited from 45 either a practical or commercial viewpoint. In my construction I have utilized the clamping device as a combined assembling means for the plug parts and a retaining means for the lead wire to the plug.

50 Having thus described my invention, I claim as new and desire to secure by Letters Patent:—

1. A spark plug, comprising an outer shell adapted to be attached to the cylinder of an 55 internal combustion engine, an insulator carrying the central electrode of the plug adapted to enter the outer shell with the central electrode in sparking relation with a grounded electrode, clamping means in-

cluding a cam for urging the outer shell 60 and the insulator toward one another and for maintaining said shell and insulator together, said clamping means also providing means for holding the lead wire to the plug.

2. A spark plug, comprising an outer 65 shell adapted to be attached to the cylinder of an internal combustion engine, an insulator carrying the central electrode of the plug adapted to enter the outer shell with the central electrode in sparking relation with a 70 grounded electrode, and clamping means including a cam for urging the outer shell and the insulator toward one another and for maintaining said shell and insulator together, said clamping means also providing 75 means for holding the lead wire to said central electrode and retaining the same in contact therewith under tension.

3. A spark plug, comprising an outer shell, an insulator received by the outer shell, 80 a grounded electrode confined between the insulator and the outer shell, a central electrode carried by the insulator in sparking relation with the grounded electrode, said insulator embodying in its construction a recessed block adapted to receive means for terminally connecting the central electrode with a lead wire, a pressure block in said recess overlying the said connecting means, and means for producing a pressure on the 85 pressure block for clamping the outer shell and the insulator together and maintaining the contact of the central electrode with the lead wire closed under tension.

4. A spark plug, comprising an outer 95 shell, an insulator received by the outer shell, a grounded electrode confined between the insulator and the outer shell, a central electrode carried by the insulator in sparking relation with the grounded electrode, 100 said insulator embodying in its construction a recessed block adapted to receive means for terminally connecting the central electrode with a lead wire, a pressure block in said recess overlying the said connecting means, 105 and means for producing a pressure on the pressure block for clamping the outer shell and the insulator together and maintaining the contact of the central electrode with the lead wire closed under tension, comprising 110 a clamping device having an annular ring engaging the outer shell, straps disposed vertical of and on opposite sides of the plug, and a cam lever having a bearing in the end of the straps and having a wiping contact 115 with said pressure block.

ALBERT A. WELLS.
